UNITED STATES PATENT OFFICE

LOUIS E. PITTONI, OF JAMAICA, NEW YORK, ASSIGNOR TO THE ROME COMPANY, INC.,
A CORPORATION OF NEW YORK

MATTRESS AND MATTRESS BOXING

Application filed May 19, 1928. Serial No. 279,188.

The present invention has for its object to improve mattresses in structure and appearance.

Mattresses are commonly provided with so-called roll edges produced by stitching 5 diagonally through the corners around the top and the bottom. Since the mattress material is comparatively soft the rib-like roll edges sag and are otherwise easily deformed 10 in use, thus detracting from the appearance of the mattress. One of the objects of the present invention is to provide a reinforcing support for a roll edge on a mattress, whereby the roll edge will maintain its original 15 shape indefinitely.

The stitches by means of which a roll edge is produced zigzag back and forth through the corner of the mattress, and not only are visible on the top and bottom and on the 20 side wall of the boxing or covering for the mattress, but they also cause the meeting lines between the roll edges and the adjacent walls of the boxing to be wavy because the material confined in the roll edges expands 25 between adjacent stitches and produces a lateral bulge. A further object of the present invention is to produce a roll edge in such a manner that the stitches will be invisible while the meeting lines between the roll edge 30 and the adjacent walls of the boxing will be straight along the four sides and be joined by smooth curves at the four corners, where the corners of the mattress are rounded. Or, viewed in another aspect, the present 35 invention may be said to have for one of its objects to produce a roll edge that will meet the adjacent walls of the boxing along lines such as would be produced by small stitches arranged close together but at the same time 40 invisible.

The sides of mattress boxings, unless they be padded, are usually simple strips of fabric that may perhaps be provided with a lining; and therefore they have a tendency to 45 become baggy. A further object of the present invention is to stiffen and reinforce the sides of a mattress boxing in such a manner that they will tend to remain straight 50 and flat, without interfering with the com-

pression and expansion of the mattress when in use.

In carrying out my invention, I provide the boxing with bead-like elements projecting from the same. These elements may be 55 in the form of cords of various sizes either concealed behind or underneath the boxing walls or sewed to the exterior of such walls. In either case, the beading may serve to ornament and thus improve the appearance of 60 a mattress.

The various features of novelty whereby my invention is characterized will herein-after be pointed out with particularity in the claims; but, for a full understanding of 65 my invention and of its objects and advantages, reference may be had to the following detailed description taken in connection with the accompanying drawings, wherein:

Figure 1 is a top plan view of a corner 70 of a mattress constructed in accordance with my invention in one of its forms; Fig. 2 is a side view of that part of the mattress shown in Fig. 1; Fig. 3 is a vertical transverse section, on a larger scale, through one 75 side of the mattress shown in Figs. 1 and 2; Fig. 4 is a view similar to Fig. 1, showing another embodiment of my invention; Fig. 5 is a section taken on line 5—5 of Fig. 4, on a much larger scale; Fig. 6 is a side elevation of a fragment of a mattress arranged 80 in accordance with a still further form of my invention; Figs. 7, 8 and 9 are elevations of fragments of strips adapted to form the sides of a mattress boxing, showing still 85 other forms of my invention; Fig. 10 is a section, on an enlarged scale, taken on line 10—10 of Fig. 9; and Fig. 11 is a view similar to Fig. 10, showing a modified arrangement.

Referring to Figs. 1, 2 and 3 of the drawing, 1 and 2 represent the top and bottom walls or sheets of a mattress boxing, and 3 the sides. The boxing is stuffed with cushioning material 4 of any usual or preferred 90 form and arrangement.

Edge rolls 5 and 6 are formed around the top and the bottom of the mattress by means of the usual diagonal stitching, indicated at 7. On the side walls of the 95

mattress are placed what may be termed beads; there being two beads 8 and 9 lying close together on opposite sides of the line of stitching to produce the top edge roll and extending entirely around the mattress.

5 When the stitches are drawn taut to compress the material of the mattress in forming the top edge roll, the two beads 8 and 9 will be drawn together, concealing the

10 stitches where they pass through the sides of the boxing. The beads also form a stiffener and support along the base of the roll edge, so that the latter will not sag but will always retain its initial shape and will

15 return to its initial condition when the mattress is relieved of the weight of a person who has been resting upon the same.

The beads 10 and 11 bear the same relation to the bottom edge roll as do the beads 20 8 and 9 to the top edge roll.

Other beads, such as indicated at 12 and 13, may extend along the sides of the boxing parallel with and in spaced relation to the beads 8 to 11; thus ornamenting and reinforcing the central portions of the sides of the boxing.

The beads may be produced in various ways. In the arrangement shown in Fig. 3, each bead consists of a heavy cord 14 sewed 30 between the material of which the sides of the mattress is made, and a lining 15 for such sides. In assembling the cords and the two sheets of fabric, the lining is preferably held so that it will remain substantially 35 flat, while the outer strip or sheet 3 is given the necessary fullness to permit it to pass over the several cords, thus producing projecting ridges or beads.

As best shown in Fig. 1, it will be seen 40 that the roll edge has an uneven appearance due to the pulling action of the stitches 7 at comparatively widely separated intervals. This uneven effect is avoided around the sides of the mattress, as is apparent from 45 inspection of Fig. 2, by reason of the presence of the beads 8 and 9. In another form of my invention, as shown in Figs. 4 and 5, I have provided the top and bottom of the mattress boxing with beads 17 and 18 lying 50 in the same positions with respect to the lines of stitching in the top and bottom walls as do the beads 8 and 9 and the beads 10 and 11 with respect to the lines of stitching 55 in the sides of the boxing. The result is that the stitches in the top and bottom of the boxing are concealed between the beads 17 and 18, and, since the beads provide a certain amount of stiffness, the cross-section 60 of each edge roll will be uniform throughout its entire length and the unevenness or bulging effect apparent in the ordinary mattress is entirely avoided.

In Fig. 6 there is illustrated a mattress 65 of any usual or suitable construction in

which the edge rolls 20 and 21 are formed in any usual way, while the sides 22 of the boxing are provided with any desired number of parallel beads 23 extending continuously around the mattress.

In Fig. 7 there is shown a sheet or strip 24 adapted to form the sides of a mattress boxing, the strip or sheet being provided with a bead 25 extending lengthwise thereof in gradual reversed curves.

In Fig. 8 a strip or sheet 26 adapted to form the sides of a mattress boxing is provided with a bead 27 extending lengthwise thereof in reversed curves, of comparatively small radius.

In Figs. 9 and 10, the strip or sheet 28 that is to form the sides of a mattress boxing has one or more beads in the form of cords 29, preferably ornamental in character, sewed to the outer side by means of 85 stitches 30. Instead of employing stitches such as shown in Fig. 10, the cord, such as indicated at 31 in Fig. 11, may be sewed to the fabric 32 by stitching 33 extending entirely through the cord down the longitudinal center of the latter.

It will thus be seen that in my improved mattress, in its most highly developed form, the stitching required to produce the edge rolls is concealed; the edge rolls are and remain uniform in cross-section throughout their lengths; and the mattress as a whole has a permanent shape of definite design, heretofore impossible on account of the character of the materials employed in making 100 a mattress. The extent of the advantages secured by the use of my invention depends upon the degree to which the several features thereof are employed. If only ornamentation and a stiffening of the sides of the boxing is desired, beads in the central zone of the strip for the sides of the boxing will suffice. So, also, the stitches on both sides of an edge roll, or on only one side thereof, may be concealed, and the concealing means may or may not serve as a stiffener; the beads being ordinarily stiffening means although they may in some cases serve simply to conceal the stitches.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A side wall for a mattress boxing comprising a fabric strip having two cord-like stiffening beads extending lengthwise thereof of close to each other at a short distance from each long edge of the strip.

2. A side wall for a mattress boxing com-

prising a fabric strip having a plurality of cord-like stiffening beads extending lengthwise thereof, there being near each long edge a pair of beads arranged close together and there being one or more beads between said

5 pairs.

3. A mattress comprising a core and a boxing therefor, parallel stiffening beads extending along the side walls of the boxing in pairs one near the top and the other near the bottom, and stitching passing through the side walls between the beads of each pair and diagonally through the corners of the mattress and the top and bottom of the boxing to produce corner rolls one margin of

15 each of which includes one of the beads.

4. A mattress comprising a core and a boxing therefor, a pair of beads placed close together extending around the top and another pair around the bottom a short distance from the edges of the boxing, other pairs of similar beads extending along the sides of the boxing a short distance from the top and a short distance from the bottom, and stitching extending diagonally through the corners of the mattress around the top and the bottom to form roll edges, the stitching passing through the boxing between the beads of each adjacent pair and

30 being concealed thereby.

5. A mattress comprising a core and a boxing therefor, two beads placed close together extending along the sides and the top and bottom of the boxing a short distance from and parallel with the upper and lower corners of the mattress, and stitching passing diagonally through the mattress near the said corners to form edge rolls, the stitching entering and leaving the walls of the boxing between the beads of the adjacent pairs.

6. A mattress comprising a core and a boxing therefor, stitching passing through the side walls and diagonally through the corner of the mattress and the top and bottom of the boxing to produce edge rolls, and cords on the boxing extending along and adjacent to at least certain of the lines containing the points at which said stitches enter and leave the mattress.

7. In a mattress comprising a core and a boxing therefor and having stitching extending diagonally through the corners to form edge rolls, narrow cord-like stiffening beads projecting outwardly from the plane of the boxing along and adjacent to at least certain of the lines containing the points at which the stitches enter and leave the boxing.

8. A mattress comprising a core and a boxing therefor, narrow heavy cords extending around the sides of the boxing a short distance from the top and bottom of the mattress, and stitching passing through said sides close to said cords and diagonally through the corners of the mattress and the

top and bottom of the boxing to produce edge rolls.

In testimony whereof I sign this specification.

LOUIS E. PITTONI. 70
